CASE FOR BEVERAGE CONTAINERS

James H. Gehl and Robert J. Stockman, Bernardsville,
and Paul E. Ralph, Somerville, N.J., assignors to Union
Carbide Corporation, a corporation of New York

Filed Jan. 25, 1966, Ser. No. 765

Term of patent 14 years

(Cl. D9—177)

Fig. 1.

Fig. 2.

Fig. 3.

FIGURE 1 is an isometric view of a case for beverage containers showing our new design;

FIGURE 2 is a top plan view of the case for beverage containers of FIGURE 1; and

FIGURE 3 is a bottom plan view of the case for beverage containers of FIGURE 1.

The sides and ends opposite the sides and ends shown in FIGURE 1 are identical.

The characteristic feature of our design resides in the particular configuration of the recessed end panel in combination with the grid portion overlying the opening therein.

We claim:

The ornamental design for a case for beverage containers, substantially as shown and described.
